Primary Examiner — George D. Kirschbaum
Assistant Examiner — Patricia K. Beard

(57) **CLAIM**

The ornamental design for a puzzle board, as shown and described.

DESCRIPTION

FIG. 1 is a front, right, and top perspective view of a puzzle board, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the puzzle board in a state of use; and,

FIG. 10 is a perspective view of the puzzle board in an alternate configuration.

The broken lines show portions of the puzzle board that form no part of the claim. The broken line showing of a “cover sheet” in FIG. 9 represents environment, and forms no part of the claimed design.

1 Claim, 10 Drawing Sheets
